UNITED STATES PATENT OFFICE.

ALONZO B. ELY, OF GROTON, NEW YORK, ASSIGNOR TO CORONA TYPEWRITER COMPANY, INC., OF GROTON, NEW YORK, A CORPORATION OF NEW YORK.

CUSHIONING DEVICE.

Application filed February 26, 1920. Serial No. 361,400.

To all whom it may concern:

Be it known that I, ALONZO B. ELY, a citizen of the United States of America, and a resident of Groton, county of Tompkins, 5 and State of New York, have invented certain new and useful Improvements in Cushioning Devices (Case No. 173), of which the following is a full and clear specification.

10 This invention relates to improvements in cushioning devices and means for connecting the same with a support.

The invention has for one of its objects the provision of a cushioning device and supporting means therefor so constructed that the cushioning device may be readily connected with and disconnected from the support.

20 Another object of the invention is to provide a cushioning device and supporting means therefor so constructed that the cushioning device may be securely connected with its support without employing extraneous fastening devices.

25 Another object of the invention is to provide a cushioning device and support having a quick detachable interlocking slip connection.

30 A further object of the invention is to provide a duplex reversible cushioning device.

Still another object of the invention is to provide a reversible resilient cushioning device having oppositely disposed dished portions forming suction gripping heads.

35 In the accompanying drawing,

Figure 1 is a bottom plan view illustrating one embodiment of the invention, in which the cushioning device serves as a cushion or foot for the main frame of a 40 typewriting machine;

Fig. 2 a horizontal section on the line II—II of Fig. 3;

Fig. 3 a transverse section on the line III—III of Fig. 1;

45 Fig. 4 a side elevation of a modified form of cushioning device having only one dished surface; and

50 Fig. 5 a perspective view of another embodiment of the invention, showing another form of duplex or reversible bumper or cushion and supporting means, therefor, adapted for use as a supporting foot for typewriters or other devices, or as a bumper for moving parts of typewriting machines, 55 or other machines or devices.

Referring to Figs. 1, 2 and 3 of the drawings by numerals, the cushioning device is formed of rubber or other suitable yieldable or resilient material and has two oppositely disposed cushioning portions or 60 heads 1 connected by a reduced cylindrical portion 2. The top and bottom faces of the cushion are dished or cupped, as shown at 3, to adapt either of the heads 1 to serve as a suction cup as well as a resilient cushion. 65 The sides of each head 1 preferably curve inwardly, as shown, from the edge of the dished face thereof to the contracted portion 2 to increase the efficiency of the gripping action of the suction cups thus formed. 70

The duplex cushion may be connected to various articles or machine frames such, for example, as the main frame of a typewriting machine. In Figs. 1 to 3, I have shown the plate-like member or support 4 to which 75 the cushion is attached as an integral extension of a horizontal flange 5 formed on the pressed steel main frame 6 of a Corona or other typewriting machine, one corner portion only of the frame being shown. 80 While I have shown the support 4 as being formed integrally with the machine frame, it will be obvious that the support may comprise a separate plate fastened to the frame in any suitable manner. 85

The support 4 is formed with a circular aperture 7 of the same, or substantially the same, diameter as the cylindrical shank portion 2 of the cushion, and said support is also formed with a throat or slot extending from one side of the aperture 7 to the outer edge of the support. The inner end of the throat at its point of connection with the aperture 7 is of less width than the diameter of the aperture and the edges 8 90 of the throat flare outwardly away from each other toward the outer edge of the support, the outer end of the throat being preferably as wide as the diameter of the aperture 7. 95

It will be obvious that the cushion may 100 be readily connected to and disconnected from the machine frame by forcing the contracted shank portion 2 laterally through slot 8 into and out of aperture 7. The inclined edges 8 of the throat serve to 105 gradually compress the contracted portion 2 of the cushion and thus increase the ease with which the cushion may be attached. As soon as the contracted portion of the cushion enters the aperture 7 it will expand 110

to its original form, filling said aperture, and thus be securely held to the frame without the necessity of employing screws, locking plates, or other extraneous fastening devices. If one head of the cushion becomes worn or damaged, the cushion may be readily detached and re-connected in reversed position.

In Fig. 4 a cushion or suction foot is shown, having a dished or cupped portion 9, similar to the heads 1 of the duplex cushion above described, connected by a cylindrical contracted shank portion 10 with a cylindrical portion or head 11 having a flat outer face.

In Fig. 5 a support 12, having an aperture and throat similar to the aperture 7 and throat 8 in the support 4, is shown. This support 12 may be a part of a machine frame, as shown in Figs. 1, 2 and 3, or may be attached to or formed on various articles or machines, or parts of machine frames, to adapt the cushion carried thereby to serve as a supporting foot, a bumper for a moving machine element, or the like. The duplex reversible bumper shown in this embodiment of the invention has two cylindrical heads 13 connected by a reduced cylindrical shank portion 14 adapted to be forced through the throat and expand in the aperture in the support.

While I have shown the heads of the cushioning device, and the reduced portion or shank connecting said heads, as circular in cross section, it will be obvious that the shape of either the heads or shank in cross-section may be varied and that the shape of the aperture 7 may be varied to conform with the shank portion 2. It will be obvious that the plate-like member to which the cushion, suction foot, or bumper is attached may be of various shapes and may be formed on or connected in various ways to machine frames and articles of various kinds. The aperture and throat in the plate-like member form, in effect, a slot open at one end and closed at the other end and having a contracted portion intermediate its ends. It will be observed also that the plate-like member and the cushion, foot or bumper are so constructed as to have a quick detachable, interlocking, slip connection that permits attachment of the foot, bumper, or cushion to the plate with either head thereof at one side of the plate.

What I claim is:

1. The combination with the frame of a typewriting machine, of a plate-like member thereon adjacent the base of the frame formed with a slot open at one end only and having a contracted portion intermediate its ends, and a cushion of resilient material having a reduced portion intermediate its ends of greater width than the contracted portion of said slot adapted to be forced

therethrough and expand in the portion of the slot intermediate said contracted portion and the closed end of the slot.

2. The combination with the frame of a typewriting machine, of a plate-like member thereon adjacent the base of the frame formed with a slot open at one end only and having a contracted portion intermediate its ends, and a cushion of resilient material having a reduced portion intermediate its ends of greater width than the contracted portion of said slot adapted to be forced therethrough and expand in the portion of the slot intermediate said contracted portion and the closed end of the slot, one end of said cushion being dished to form a suction gripping head.

3. The combination with the frame of a typewriting machine, of a reversible rubber foot having two oppositely disposed support-engaging heads and a reduced intermediate portion, and means on said frame having an interlocking lateral slip connection with the reduced portion of said foot.

4. The combination with the frame of a typewriting machine, of a rubber foot having a reduced portion intermediate its ends and a dished support-engaging portion at one end, and means carried by the frame having an interlocking slip connection with the reduced portion of said foot.

5. The combination of a reversible supporting member having two oppositely facing suction heads, and a rigid plate-like attachment member extending transversely of the reversible supporting member and having a lateral slip connection therewith.

6. The combination with a machine frame of a reversible supporting foot having two oppositely facing suction heads adapted to grip a supporting surface, and means forming an interlocking slip connection between said foot and frame.

7. The combination of a member having a slot therein open at one end only and having an intermediate contracted portion, and a resilient cushioning device having two cushioning heads and an intermediate reduced portion of greater width than the contracted portion of the slot adapted to be forced into the slot beyond the contracted portion thereof.

8. The combination of a member having an aperture therein and a slot extending from one edge of said aperture to the outer edge of said member, and an inherently resilient cushioning device having a reduced portion of greater width than said slot adapted to be forced through the slot and expand in said aperture.

9. In a printing machine, the combination of a main frame having an integral horizontally extending portion adjacent its lower edge provided with a circular aperture and a slot leading from the aperture to

one edge of said horizontal portion, said slot gradually increasing in width toward its outer end and being of less width than the diameter of said aperture at its inner end, and a detachable rubber supporting foot having a reduced compressible cylindrical shank portion engaged in said aperture, said shank portion of the foot being of substantially the same length as the thickness of the horizontal portion of the frame ¹⁰ and of substantially the same diameter as the aperture.

This specification signed this 19th day of Feb., A. D. 1920.

ALONZO B. ELY.
